UNITED STATES PATENT OFFICE

FREDERICK W. RETTENMEYER, OF MERIDEN, CONNECTICUT, ASSIGNOR TO THE
NAPIER COMPANY, OF MERIDEN, CONNECTICUT, A CORPORATION

DESIGN FOR A METAL UNIT FOR JEWELRY

Application filed December 16, 1929. Serial No. 33,799. Term of patent 3½ years.

To all whom it may concern:

Be it known that I, FREDERICK W. RETTENMEYER, a citizen of the United States, residing at Meriden, in the county of New Haven and State of Connecticut, have invented a new, original, and ornamental Design for a Metal Unit for Jewelry, of which the following is a specification, reference being had to the accompanying drawing, forming part thereof.

Fig. 1 is a face view in detail of a metal unit for jewelry, other similar units being shown by broken lines as connected thereto, showing my new design; and

Fig. 2 is an edge view of the same.

I claim:

The ornamental design for a metal unit for jewelry, as shown and described.

FREDERICK W. RETTENMEYER.
